UNITED STATES PATENT OFFICE.

JASPER BLACKBURN, OF WEBSTER GROVES, AND ARTHUR ALBRECHT AND HEReward J. PEELE, OF ST. LOUIS, MISSOURI; SAID ALBRECHT AND SAID PEELE ASSIGNS TO SAID BLACKBURN.

INSULATOR SUPPORT.

Application filed July 2, 1927. Serial No. 203,234.

Our invention relates to improvements in insulator supports, and has for its primary object a support for carrying insulators designed for supporting telegraph, telephone and other electrical wires, and which is capable of being easily applied to a brick or stone wall.

A further object is the construction of an insulator support for carrying an insulator so that the longitudinal axis of the insulator may be arranged to occupy various positions to the wall to which it is applied and so that the grooves of the insulator in which the conductors are located may be arranged to occupy various positions and the conducting wires may be applied to the insulator in a plane substantially in line with the longitudinal axis of the conductor so that the conductor wires will not be marred or cut by the walls of the grooves.

In the drawings:

Fig. 1 is a fragmental section of a brick wall including a portion of a joint or seam illustrating the application of our insulator support in the horizontal seam or joint of the wall with an insulator mounted thereon, and its axis extending in a vertical direction;

Fig. 2 is a similar view with the support arranged in the vertical seam or joint of a wall illustrating the insulator so that its longitudinal axis is arranged at an angle less than a right angle to the face of the wall;

Fig. 3 is a similar view showing our insulator support arranged in the vertical seam or joint of a wall with the insulator projecting downwardly from the wall and having its axis arranged to the face of the wall at an angle less than a right angle;

Fig. 4 is a similar view showing a plan of our insulator in a horizontal seam showing the insulator located in a horizontal position and its axis extending at an angle to the vertical face of the wall; and

Fig. 5 is a perspective view of the support with the insulator removed.

Referring to the drawings, our insulator support is preferably formed of sheet metal and consists of a head portion 7 in which is formed an opening 8 for the insertion of a bolt 9 for securing the insulator to the support. The head portion 7 is provided with an extension 10, which is folded or bent as at 11 so as to form a spring tongue 12. The spring tongue 12 is provided with a bend 13. The tongue when formed is spaced away from

the extension 10 so that it can spring downwardly. When the insulator is driven into the joint or seam of a wall, the tongue 12 will occupy substantially the position as illustrated in Fig. 1, that is to say, its free end 60 will impinge against the top surface of the extension 10 and the bend 13 will be somewhat flattened out. As the tongue is formed of resilient and elastic material, when it is driven into position as illustrated in Fig. 1, 65 it will securely hold the insulator support in position.

Formed integral with the head 7 is an angular extension 14 which extends substantially at right angles to the head and in which 70 there is formed an opening 15 for receiving a bolt to secure the insulator. Between the extension 14 and the extension 10 is a shoulder 16, which limits the extent to which the insulator may be driven in the joint or seam 75 and also acts as a brace for the insulator support.

It will be noted that the extension 10 of the head 7 extends in a different direction from the extension 14 and the insulator may 80 be secured by means of the bolt 9 to the head 7 of the insulator or it may be secured by means of a bolt to the extension 14.

When the insulator is secured to the support as illustrated in Fig. 1, it is to be understood that the insulator is supported in a vertical position so as to receive conductor wires leading to it in a horizontal direction. When the insulator is secured to the extension 14 and the support is secured in the vertical seam 85 or joint of a wall as illustrated in Fig. 2, it will be noticed that the insulator is arranged to receive conducting wires extending upwardly in an angular direction, and when the support is located in the vertical seam of a wall and the insulator extends downwardly, 90 it is adapted to receive conductors extending downwardly in an angular direction as illustrated in Fig. 3. When the support is positioned in the horizontal seam or joint of a wall and the insulator is connected to the extension 14, it is arranged to receive conductors leading in a horizontal direction at an angle to the face of a building as illustrated 95 in Fig. 4.

By being able to insert the support either in the horizontal seam or joint, or in the vertical seam or joint, and with the extension 14 to which the insulator is secured, as well as the head to which it may be secured, the insulator 100 105 110

may be so disposed that the grooves thereof will properly receive the conducting wires coming or leading from various directions.

In Figs. 1, 2, 3 and 4 we have illustrated by dotted lines the various directions or positions of the electrical conductors, and it is always essential that the relative positions of the grooves and the conductors be such that the conductors will fit in the grooves and will not be bent or kinked by the walls or edges of the grooves.

It will be noted that by our construction the head portion is substantially rectangular in plan view and that one corner thereof is bent at an angle to the plane of the head portion so that this bent portion will be bent at an angle, either a right angle or any other angle, to the plane of the head.

The extension 10 is on the same plane as the head portion 7 while the tongue, which is formed integral therewith, extends longitudinally of the portion 10 and toward the head, the free end of this tongue however being spaced sufficiently above the portion 10 so that it can move downward without binding on the portion 10, it being understood, of course, that our device is constructed of spring metal so that various portions thereof will be resilient or springy.

An important feature of our device is that it is formed of a single piece of metal which has an inherent spring quality so that any of the gripping portions will act without the necessity of any additional treatment to render them resilient or springy.

Having fully described our invention, what we claim is:—

1. An insulator support formed of a single piece of metal, said support being provided with a head portion, a forward extension bent over on itself, the bent over portion being provided with a bend, a shoulder formed on the head and arranged in proximity to and parallel with the free end of the bent over portion, a triangular extension bent substantially at a right angle to the head, said ex-

tension being arranged at an angle less than a right angle to the longitudinal axis of the first mentioned extension and the bent over portion.

2. An insulator support formed of a single piece of metal and composed of a head portion provided with an opening and with an integral narrow extension, a resilient tongue formed integral with said extension and having its free end extending towards the head, an angular extension formed integral with the head portion, and bent at right angles thereto, the line of the bend being arranged diagonally to the longitudinal axis of the forward extension and tongue, whereby upon the positioning of the support and its accompanying insulator either in the horizontal or vertical seam of a wall the grooves of the insulator may be positioned to receive conducting wires leading or extending from various directions.

3. An insulator support formed of a single piece of spring metal and composed of a head portion rectangular in plan and having one of its corner portions bent diagonally and at an angle to the plane of the head, said head portion and corner portion each being provided with a bolt receiving opening, and a folded tongue portion, said tongue portion being narrower than the head portion and integral with said head portion.

4. An insulator support formed of a single piece of spring metal and composed of a head portion, rectangular in plan and having one of its corner portions bent diagonally and at right angles to the plane of the head, said head portion and corner portion each being provided with a bolt receiving opening, and a resilient folded tongue portion integral with and of less width than said head portion.

In testimony whereof we have affixed our signatures.

JASPER BLACKBURN.
